UNITED STATES PATENT OFFICE.

RUSSEL G. WOODWARD, OF WAUKEGAN, ILLINOIS, ASSIGNOR TO UNION SPECIAL MACHINE COMPANY, OF CHICAGO, ILLINOIS, A CORPORATION OF ILLINOIS.

PRESSER-FOOT FOR SHIRRING-MACHINES.

1,145,645.

Specification of Letters' Patent.

Patented July 6, 1915.

Application filed May 5, 1908. Serial No. 430,399.

To all whom it may concern:

Be it known that I, RUSSEL G. WOODWARD, a citizen of the United States, residing at Waukegan, in the county of Lake, State of Illinois, have invented certain new and useful Improvements in Presser-Feet for Shirring-Machines, of which the following is a description, reference being had to the accompanying drawing and to the letters and figures of reference marked thereon.

My invention relates to new and useful improvements in shirring machines, and more especially to the presser foot used in connection with machines of this type.

15 The object of my invention is to provide a presser foot which may be used to shirr the fabric operated upon or which may be so adjusted as to perform ordinary sewing.

20 A further object of my invention is to provide a presser foot for shirring fabric, which has adjustable parts so that the size of the shirrs being formed may be varied.

25 A still further object of my invention is to provide a presser foot for forming shirrs which may tilt to accommodate seams extending at an acute angle to the line of feed.

Still further objects of my invention will in part be obvious, and will in part be more fully hereinafter described.

30 In the drawings which show by way of illustration one embodiment of my invention: Figure 1 shows the head of a sewing machine with certain parts in section, with my improved presser foot applied thereto.

35 Fig. 2 is a top plan view of the presser foot showing a strip of fabric with a seam therein, extending diagonally of the line of feed. Fig. 3 is a sectional view of my improved presser foot with the parts adjusted for

40 shirring. Fig. 4 is a detail front view of the auxiliary presser foot. Fig. 5 is a view of the presser foot from the rear. Fig. 6 is a view of the presser foot from the front with the main portion in section. Fig. 7 is a view

45 similar to Fig. 3 with the parts in position for plain stitching. Fig. 8 is a detail in side elevation, showing a modified form of means for adjusting the foot. Fig. 9 is a plan view of the adjusting wheel shown in Fig. 8.

50 Fig. 10 is a detail, showing in side elevation, a further modification of the adjusting device. Fig. 11 is a plan view of the same. Fig. 12 shows treadle connection to adjusting lever.

55 My improved presser foot may of course,

be used in connection with a sewing machine of any desired type. For the sake of illustration, I have however, shown my foot applied to a multiple needle single chain stitch machine. Said machine comprises a needle 60 bar 1, which is reciprocated in the usual manner, and carries a needle 2. The presser bar 3, is mounted in the forward end of the machine, and is lifted in the usual manner, by the presser lever 4. Said presser bar is 65 provided with a presser foot 5, which cooperates with a feed dog 6, carried by a feed bar 7, and operated in the usual manner. A looper 8 is mounted beneath the work support 9, and cooperates with the needle 2. 70 These parts with the exception of the presser foot, are of the usual construction and will not need further description in this connection.

My improved presser foot is made in two 75 parts 10 and 11. The main part 11, as shown in the present illustrated embodiment of my invention, is provided with an upwardly extending shank portion 12. Said shank portion 12, extends up through a supporting frame or collar 13, formed integral with the split clamping arm 14, which secures the presser foot to the lower end of the presser bar. Said presser bar is secured to the supporting frame 13 by a pivot pin 15. 80 The lower face of the frame 13 tapers upwardly from its center outward as shown in Figs. 5 and 6. It will therefore, be seen that the main part 11 of my foot is capable of a slight tilting movement in a direction substantially at right angles to the line of feed. 85

As shown in the drawings, the main part 11 is a wide foot, containing five needle holes 16, each of which is adapted to receive a needle of the stitching mechanism. It will 95 be obvious however, that from certain aspects of my invention said foot may be much narrower and used in connection with a single needle, if desired.

It will be noted that the needle holes 16, 100 are located in the foot at the extreme rear portion of the contact part 17 of the main portion of the foot. In rear of the needle holes 16, the foot is cut away so as to form a space. Located in said space is an 105 auxiliary foot 18, which may be adjusted vertically so as to close said space more or less when desired. For certain characters of work, it is desired to have the auxiliary foot 18 flush with the contact surface 17 of the 110

main foot 11. This makes of my foot, practically an ordinary presser foot, so that the machine may be operated to produce plain sewing. When however, the auxiliary part 18 is adjusted up away from the plane of the contact part of the main presser foot, then, the fabric in rear of the stitching point will be released from all pressure. As a result the fabric will be fed to the stitching point, but there is nothing to immediately feed the fabric away from the stitching point, so that said fabric will pile up, thus making shirrs. The amount of piling up of the fabric which determines the size of the shirrs will vary according to the position of the auxiliary part 18 of the foot. When said part is adjusted so that the space in rear of the stitching point is greater, of course, more fabric will be piled up before it is fed away from the stitching point, and thus the size of the shirrs increases, while on the other hand, if the space be decreased, the size of the shirrs will be correspondingly decreased.

As a means for adjusting the auxiliary part 18 of my foot, I have provided said part with a shank portion 19, which extends up into the tubular shank 12 of the main presser foot 11. Said shank portion 19, as shown in Figs. 3 and 7, is provided with an elongated opening 20, which surrounds the pivot pin 15. The upper portion of the shank 19 is provided with a threaded socket which receives a screw 21. Said screw 21 is provided with a collar 22, and a head whereby it may be turned. The collar 22 is spaced slightly from the head and a bracket 24 secured to the shank 12 of the main presser foot by screws 25, extends between said head and said collar and serves to hold the screw 21 against longitudinal movement. It will be obvious therefore, that as the screw 21 is rotated, one way or the other, the shank 19 of the auxiliary presser foot will be raised and lowered. The opening 20 in the shank 19 will however, engage the pin 15 and serve as a stop to limit the vertical movement of the shank 18. Said opening 20 is so disposed that when the pin 15 is brought into contact with the upper side of said opening, the lower face of the auxiliary part 18 lies in the same plane as the contact portion 17 of the main foot. As a means for rotating the screw 21, I have provided the head with a plurality of openings 26.

In Figs. 8 and 9, I have shown a modified form of means for adjusting the screw 21. In this form of my invention, the screw 21 is provided with a small gear wheel 27 which meshes with the gear wheel 28 connected to a thumb wheel 29 which is mounted on the presser bar so as to rotate freely thereon. By rotating said thumb wheel, the screw 21 will be also rotated and the aux-

iliary portion of the foot adjusted. It will be obvious that the regulating thumb wheel 29 may be operated without stopping the action of the stitching mechanism, if desired.

In the operation of a shirr foot of the character herein shown, it has been noted in passing over a seam which extends diagonally, that an irregularity in the shirring occurred, for the reason that one end of the seam raised the whole presser foot up, and it remained elevated on the seam until said foot passed over the opposite end of the seam. By my improved presser foot however, wherein the foot may tilt in the direction at right angles to the feed, a seam such as above noted, rocks the foot one way, as it passes under the foot, and rocks the foot the other way before passing from under the foot, and thus controls the fabric and the shirring at all times.

In Fig. 10, I have shown a still further modified form of means for adjusting the auxiliary foot 10. The sewing machine operator often finds it desirable to stitch a ruffled strip which is continuous, that is without end, to the body or flounce of the skirt, which is also continuous. A ruffled strip of this character, is made somewhat larger than the body of the skirt to which it is attached, and the operator is expected to gather in the ruffled strip so as to make the ruffled strip lie flat on the body portion of the skirt. This can readily be accomplished on my improved shirring machine, and more especially by the mechanism disclosed in Figs. 10 to 12. The shank 12 of the main part of the presser foot, 5, extends only a slight distance above the collar 13. The shank of the auxiliary presser member 10 extends up through the tubular shank 12 of the main presser foot, and carries a collar 30. A spring 31 surrounds the shank 19 of the auxiliary presser member and bears against the collar 30 at one end, and against the tubular shank 12 of the main foot, at the other end. It will readily be seen that the spring normally holds the auxiliary foot raised so as to form a space in the rear of the stitching point, thus allowing the machine to form shirrs. A lever 32 is pivoted at 33 to the head of the machine, and the forward end 34 of the lever is bent laterally (see Fig. 11), and rests on top of the collar 30. A spring 36 is secured to a lug 37 on said lever 32 at one end, and to a lug 38 on the head of the machine at the other end. Said spring 36 is considerably heavier than the spring 31 and normally holds the outer end of the lever 32 raised and the spring 31 compressed, so that the lower face 18 of the auxiliary presser member, is flush with the contact face 17 of the main foot 11, so that the machine will do plain stitching. A treadle 39 mounted underneath the support for the machine, is connected to the lever 32

by a rod 40, and a spring 41 may be provided for holding said treadle with the rear end thereof, raised. It will readily be seen, that the operator may tilt the treadle 39, thus lowering the outer end of the lever 32, which in turn will raise the forward end of said lever and allow the spring 31 to raise the auxiliary foot 18, so that the machine will form shirrs in the material operated upon. The size of the shirrs will depend upon the extent to which the treadle is depressed. Upon releasing the treadle, the springs 36 and 41 will immediately operate to depress the spring 31 which will lower the auxiliary foot, and stop the shirring action.

When joining a continuous ruffled strip to the body of a skirt as above noted, the operator may without stopping or retarding the machine, cause a shirring operation to be performed or not, just as desired, and thus full in or gather the ruffled strip sufficiently so that it will lie smooth and flat upon the body of the skirt.

While the above mechanism is especially useful in joining ruffled strips to skirt bodies, it is obvious that it may be used wherever it is desired to form shirrs and that by this mechanism, an operator can, without retarding the speed of the machine, form shirrs which vary in size or do plain stitching.

While I have shown my presser foot as made in sections which are adjustable relative to each other, for the purpose of forming shirrs, it will be obvious that the space in rear of the stitching mechanism might be formed by other means, the essential feature being the continuous feeding of the fabric in front of the stitching point, and the retarding feed of the fabric in rear of the stitching point, caused by the space between the presser foot and the member with which it cooperates in feeding the fabric, and the means for adjusting the retarding action.

Having thus particularly described my invention, what I claim as new and desire to secure by Letters Patent, is:—

1. A sewing machine including in combination, a work support, stitch forming mechanism having a needle, feeding mechanism engaging the under face of the fabric in front of and in rear of the needle, said feeding mechanism having a uniform movement throughout, means above the work support cooperating with the feeding mechanism in rear of the needle for causing said feeding mechanism to shirr a single strip of fabric, and means for varying the said shirring action for rendering the same ineffective whereby plain stitching may be produced.

2. A sewing machine including in combination, a work support, stitch forming mechanism having a needle, feeding mechanism engaging the under face of the fabric in

front of and in rear of the needle, said feeding mechanism having a uniform movement throughout, means above the work support cooperating with the feeding mechanism in rear of the needle for causing said feeding mechanism to shirr a single strip of fabric, and means for varying the said shirring action for rendering the same ineffective whereby plain stitching may be produced, said last named means being under the control of the operator without stopping the stitch forming mechanism.

3. A sewing machine including in combination, a work support, stitching mechanism, feeding mechanism, and a presser foot cooperating with said feeding mechanism, said presser foot including a main part engaging the fabric in front of the stitching point, and an auxiliary part located and engaging the fabric in rear of the stitching point, and means for adjusting the auxiliary part relative to the main part toward and from a position flush with said main part.

4. A sewing machine including in combination, a work support, stitching mechanism, feeding mechanism and a presser foot cooperating with said feeding mechanism, said presser foot including a main part, engaging the fabric in front of the stitching point, and an auxiliary part located and engaging the fabric in rear of the stitching point, and means for adjusting the auxiliary part relative to the main part toward and from a position flush with said main part, said last named means being under the control of the operator and capable of operation without stopping the action of the stitching mechanism.

5. A sewing machine including in combination, a work support, stitching mechanism, feeding mechanism, a presser foot cooperating with the feeding mechanism, said presser foot including a main part for engaging the fabric in front of the stitching point, an auxiliary part in rear of the stitching point, means for adjusting said auxiliary part relative to the main part, and a stop for limiting the movement of the auxiliary part so that the contact face thereof, may be brought into the plane of the contact face of the main part.

6. A sewing machine including in combination, a work support, stitching mechanism, feeding mechanism, a presser foot cooperating with the feeding mechanism; said presser foot including a main part for engaging the fabric in front of the stitching point, an auxiliary part in rear of the stitching point, means for adjusting said auxiliary part relative to the main part, and a stop for limiting the movement of the auxiliary part, so that the contact face thereof may be brought into the plane of the contact face of the main part, the means for adjusting the auxiliary part being under the

control of the operator and capable of operation without stopping the stitching mechanism.

7. A sewing machine including in combination, a work support, stitching mechanism, feeding mechanism, a presser foot co-operating with the feeding mechanism, said presser foot including a main part for engaging the fabric in front of the stitching point, an auxiliary part in rear of the stitching point, means for adjusting said auxiliary part relative to the main part, and a stop for limiting the movement of the auxiliary part, so that the contact face thereof, may be brought into the plane of the contact face of the main part, said means for adjusting the auxiliary part including a lever and a treadle connected to said lever for operating the same.
20. 8. A sewing machine including in combination a work support, stitching mechanism, feeding mechanism, a presser foot co-operating with the feeding mechanism, said presser foot including a main part for engaging the fabric in front of the stitching point, an auxiliary part in rear of the stitching point, means for adjusting said auxiliary part relative to the main part, and a stop for limiting the movement of the auxiliary part so that the contact face thereof, may be brought into the plane of the contact face of the main part, said means including a lever pivoted to the head of the machine, a spring for moving said lever in one direction, and a treadle connected to said lever for moving the same in the opposite direction.

9. A sewing machine including in combination, a work support, stitch forming mechanism having a needle, feeding mechanism engaging the under face of the fabric in front of and rear of the needle, said feeding mechanism having a uniform movement throughout, a presser foot, said presser foot including means located in rear of the needle and co-operating with the feeding mechanism whereby said feeding mechanism is caused to shirr the fabric, and means for adjusting the shirring action for rendering the same ineffective at the will of the operator.

50. 10. A sewing machine including in combination, a work support, stitching mechanism, feeding mechanism, a presser foot co-operating with said feeding mechanism and including a main part and an auxiliary part in rear of the stitching point, capable of vertical adjustment, whereby the machine may be caused to shirr the fabric, a spring for normally holding said auxiliary part in raised position, a stop for limiting the downward movement of said auxiliary part, so that the contact face thereof may be moved into the plane of the contact face of the foot.

11. A presser foot for sewing machines, 65 including a main foot having a needle hole

and a contact surface in front of said needle hole and an auxiliary foot in the rear of the needle hole, and means for adjusting said auxiliary foot, whereby the contact face thereof may be raised above the plane of the 70 contact face of the main foot and means for holding the parts in adjusted positions.

12. A presser foot including in combination, a main fabric-engaging part and an auxiliary fabric-engaging part located entirely in rear of the main fabric-engaging part, and means for adjusting the auxiliary part toward and from a position flush with the main part, whereby the same may be 75 spaced from the material.

13. A presser foot including in combination a supporting member and a foot portion secured to said supporting member so that said foot portion may have a rocking transverse movement, said foot portion including 85 a main part and an auxiliary part, and means for adjusting the auxiliary part relative to the main part whereby said auxiliary part may be spaced from the material.

14. A presser foot including in combination, a supporting part, a foot portion pivoted thereto, said foot portion including a main part and an auxiliary part in rear of the main part, and means for adjusting the auxiliary part relative to the main part 95 whereby the auxiliary part may be spaced from the material.

15. A presser foot including in combination, a clamping arm, a supporting collar secured thereto, a presser foot having a shank 100 extending up through said supporting collar, and a pin supported by the collar and extending through said shank whereby said presser foot may rock transversely, said presser foot including a main part, and an auxiliary part and means for adjusting the auxiliary part relative to the main part.

16. A presser foot including in combination a main part having a needle hole, an auxiliary part in the rear of said needle hole, said auxiliary part having a shank extending up through the main part, a stop for limiting the downward movement of the auxiliary part, and means for raising and lowering said auxiliary part.

17. A presser foot including in combination a main part having an upwardly extending shank, a supporting member to which said shank is pivoted, a pivot-pin for securing the shank to the supporting member, an auxiliary part having a shank extending up through the shank of the main part and having an elongated opening through which the pivot pin passes and means for adjusting said auxiliary part.

18. A presser foot including in combination a main part, having an upwardly extending shank, a supporting member to which said shank is pivoted, a pivot pin therefor, an auxiliary part, having a shank 130

extending up through the shank of the main part, said shank of the auxiliary part having an elongated opening to receive said pivot pin and to limit the movements of said auxiliary part, and means for adjusting said auxiliary part.

19. A sewing machine including in combination, a presser foot, having a main part, a shank extending upwardly from said main part, and having an opening therein, an auxiliary part having a shank extending up through the opening in the shank in the main part, a spring for normally holding said auxiliary part in raised position, and a lever for depressing said auxiliary part.

20. A sewing machine including in combination a presser foot having a main part, a shank extending upwardly from said main part and having an opening therein, an auxiliary part having a shank extending up through the opening in the shank in the main part, a spring for normally holding said auxiliary part in raised position and a lever for depressing said auxiliary part, and stops for limiting the movements of the auxiliary part.

21. A sewing machine including in combination, a presser foot having a main part, a shank extending upwardly from said main part, a supporting member to which said shank is pivoted, an auxiliary part having a shank extending up through the shank in the main part, a collar secured to the upper end of the shank of the auxiliary part, a spring interposed between said collar and the shank of the main part.

22. A sewing machine including in combination, a presser foot, having a main part, a shank extending upwardly from said main part, a supporting member to which said shank is pivoted, an auxiliary part having a shank extending up through the shank in the main part, a collar secured to the upper end of the shank of the auxiliary part, a spring interposed between said collar and the shank of the main part, and a lever piv-

oted to the head of the machine, and having an arm normally resting upon said collar, and a spring of greater tension than the spring on the shank of the auxiliary part 50 and operating to hold the contact face of the auxiliary part normally in the plane of the contact face of the main part.

23. A sewing machine including in combination, a work support, stitching mechanism, feeding mechanism, a presser foot co-operating with said feeding mechanism, said presser foot being formed of two parts acting against the fabric, one portion being arranged in advance of the other, means to 60 vertically adjust the rear portion relative to the forward portion, the line of separation of the two portions being at the needle hole.

24. A sewing machine including in combination, a work support, stitching mechanism including a needle, a presser foot, means for feeding the fabric to said needle, and adjustable means in rear of the needle and co-operating with the needle and said feeding means for shirring the fabric, said 70 needle passing through the presser foot at a point slightly in advance of the adjustable means.

25. In a sewing machine, a work support, stitching mechanism, a presser foot, said 75 presser foot having a fabric-engaging portion in rear of said stitching mechanism elevated above the plane of the bottom of the fabric-engaging portion of said presser foot in front of the stitching mechanism, said 80 fabric-engaging portions being fixed relative to each other during the normal action of the stitching mechanism, and means whereby said presser foot can rock transversely. 85

In testimony whereof I affix my signature, in presence of two witnesses.

RUSSEL G. WOODWARD.
